UNITED STATES PATENT OFFICE

JAMES P. TAYLOR, OF BROOKLYN, NEW YORK

BLOW DISTRIBUTING ATHLETIC PROTECTOR

Application filed March 15, 1930. Serial No. 436,124.

This invention relates to athletic protectors of the type necessary for the protection of males in such sports as boxing, hockey, football, and the like.

The principal object of the invention is to combine in one unitary structure means capable of yielding with resistance to a localized blow, distributing the localized force of such blow substantially uniformly over a large area, of a shape retaining member physically capable of contacting with the part to be protected and then yieldingly resisting the aforesaid distributed force over a distributed area or non-sensitive portions of the human anatomy. To this end, I propose to combine with a protecting cup of rigid material such as a cast shell of duraluminum, a shell of fiber, a shell of molded hard rubber composition, or a shell of bakelite, or the like, an outer yielding and distributing member preferably employing the principle of pneumatics and preferably in the form of an outer membrane spaced from the unyielding cup by means of a chamber or chambers filled with gas under pressure and so interconnected that a localized blow will have its force distributed substantially over the entire surface area of the cup, and with an inner yielding member attached to the rim of said cup and adapted to rest upon the body of the wearer.

In the use of my protector, I have found that it is best to rely upon the usual elastic bandage or strap worn by athletes to hold my protector in position on the wearer, although I, of course, contemplate the possibility of providing a similar elastic attaching means attached to or formed as a part of my entire structure.

A further object of my invention, and in fact its prime object, is to safeguard an athlete from distress from practically any blow so far as his sensitive parts are concerned.

The above and further objects of the invention will be understood better from the following description of preferred embodiments of my invention which are described in connection with the accompanying drawings which form a part hereof. It is to these illustrative embodiments of the invention

that the following claims are directed solely for purposes of illustration and not limitation.

In the drawings, Fig. 1 is a front elevation partly in perspective and somewhat diagrammatic with parts shown in dotted lines indicating the wearing position of my protector with an elastic bandage for holding it in place; Fig. 2 is a vertical cross-section taken at right angles to the position in Fig. 1 through an embodiment of my invention, and more specifically taken through the line of II-II of Fig. 3; Fig. 3 is a horizontal section through the plane of line III-III of Fig. 2; Fig. 4 is an enlarged vertical section like Fig. 2 of a modification; and Fig. 5 is a similar vertical cross-section through a preferred modification.

Referring now more in detail to the drawings, A indicates a usual form of elastic bandage or supporting strap comprising a belt 1 of elastic webbing; rear leg straps 2 and 3; and a front broad elastic strap 4 extending from the front of the belt 1 to the lower ends of the straps 2 and 3. This functions to press the protector B into operative position upon the wearer.

In the embodiments of Figs. 2 and 3, a protector cup 5 formed of any of the materials heretofore enumerated, preferably cast aluminum, may have any desired shape to form a safety cavity 6. A proper shape is indicated by the contours shown in Figs. 2 and 3. To give lightness, it is preferred that perforations 7 be formed in this unyielding cup.

A pneumatic blow distributor 8 has one wall 9 cemented to the outer face of the cup 5 and its spaced outer wall 10 overlying the same and provided with any suitable form of inflating nipple 11. An inner lining 12 is cemented to the inner face of the cup and an inner outstanding rim 13, preferably of sponge rubber, is vulcanized to the rim of the previously described construction. In addition to the rim 13 it is preferred that an additional top pad 14 having wings 15 and 16 extending out laterally be provided to assist in distributing the rearward force from a

blow over impervious portions of the wearer's body.

In the construction shown in Figs. 2 and 3, the lining 17 may be chamois or rubber, whereas the bladder having the parts 9 and 10 is preferably of a high grade of rubber similar to that employed for the making of inner tubes for automobile tires.

In Fig. 4, the outer membrane 100 is preferably of tough rubber like the outer membrane 10 but instead of the open pneumatic cavity, a filling 101 of sponge rubber made up of cells containing gas under pressure is distributed over the outer face of the cup 5 and is preferably a continuation of an inner lining of rubber 102. The inner cushioning rim 13 is provided and also preferably the distributing pad 14.

In Fig. 5, a unique construction lending itself to quantity production is illustrated. In this construction the cup 50 is preferably provided with a broad-faced inner flange 51 to which a cushioning flange of sponged rubber is cemented or vulcanized. First an outer plate 53 of sheet rubber is applied to the outer face of the cup and then the inner wall 54 of a blank of sheet rubber is vulcanized through the perforations 55 of the cup 50 to the outer sheet 53 so that the rubber parts 56 passing through the perforations form a strong anchorage to hold the resilient flexible rubber parts together.

The outer part of a pneumatic protector is in the form of a sheet rubber blank 57 provided with the inflating nipple 11 and has its terminal rim 60 overlying the terminal rim 61 of the inner wall 54, the overlapping portions of which rims are preferably vulcanized together, and if desired, also to the sponge rubber cushioning flange 52. In this construction, a part of the pneumatic structure serves as the inner lining as well as a part of the inclosure for the air under pressure. With this construction, it is contemplated that the shaping of the sheet rubber walls be such as to enable the cavity 70 to be filled with compressed air or other gas under considerable pressure, even as high as twenty pounds per square inch. This facilitates in distributing the force of a localized blow. It is, of course, to be understood that the resistance of the sheet rubber walls against stretch may be varied in accordance with good rubber manufacturing principles to aid in retaining the desired shape for the finished article.

In its functioning, a blow localized, for example, at the arrow 80 first causes a considerable yielding of the wall 57 at this locality, but no blow as from a fist or knee or boot can affect the yielding of this wall sufficiently to make direct contact with the unyielding wall 50. Work, of course, is done in effecting this local yielding of the outer wall

57 which tends to annul the force of the blow, but in addition, an important functioning is the distribution of the force of the blow over the entire outer surface 81 so that in turn a substantially uniform moderate pressure per square inch is directed towards the body through the cushioning flange 52. Besides this, the cushioning flange 52 contacts only with the non-sensitive portions of the wearer's body and further work is caused to be done in the compressing of this cushioning flange 52 before the body itself must take up the force of a localized blow. In no event can the cup 50 yield to make direct contact with the more sensitive parts of the wearer. I therefore have distributed a localized blow and caused it to do work first in the pneumatic forming unitary part of the structure and then in the body contacting cushion and lastly in the blow resisting parts of the body itself. In fact, I have found my protector so perfect that for a year I have successfully maintained myself against personal injury in submitting to an open challenge to receive any kick, knee or fist blow upon this protector when personally wearing it.

What I claim and desire to secure by United States Letters Patent is:

1. An athletic protector in the form of a unitary structure comprising, a protecting cup of unyielding material having a body facing flange and an outwardly bulging portion; an outer member permanently secured to said cup and providing a cavity, which cavity has a filling of force distributing material adapted to distribute the force of a localized blow substantially uniformly over the entire outer surface of said cup; and an inner yielding means fixed to said cup and localized between the body facing rim of said cup and the body of the wearer whereby the force of a localized blow is first distributed about the outer surface of said unyielding cup and then a yielding movement of said entire cup takes place and is cushioned substantially throughout the entire extent of said cushioning means between the body facing rim of said cup and the body of the wearer.

2. An athletic protector in the form of a unitary structure comprising, a protecting cup of unyielding material having a body facing flange and an outwardly bulging portion; an outer member permanently secured to said cup and providing a cavity, which cavity has a filling of gas under pressure adapted to distribute the force of a localized blow substantially uniformly over the entire outer surface of said cup; and an inner yielding means fixed to said cup and localized between the body facing rim of said cup and the body of the wearer whereby the force of a localized blow is first distributed about the outer surface of said unyielding

cup and then a yielding movement of said entire cup takes place and is cushioned substantially throughout the entire extent of said cushioning means between the body facing rim of said cup and the body of the wearer.

JAMES P. TAYLOR.
